UNITED STATES PATENT OFFICE.

ROBERT H. LIEBERTHAL, OF BRIDGEPORT, CONNECTICUT, ASSIGNOR TO THE ALL-IN-ONE MANUFACTURING COMPANY, INCORPORATED, OF BRIDGEPORT, CONNECTICUT.

COLLAPSIBLE TUBE.

Application filed August 3, 1923. Serial No. 655,466.

To all whom it may concern:

Be it known that I, ROBERT H. LIEBERTHAL, a citizen of the United States, residing at Bridgeport, county of Fairfield, State of

5 Connecticut have invented a new and useful Collapsible Tube, of which the following is a specification.

This invention relates to collapsible tubes of the type used for holding paste or liquids, 10 such as tooth paste, shaving cream, paints and so forth, and particularly to the discharge nozzle for these tubes and the means for sealing the same.

When these tubes are used for tooth paste 15 the pure food laws require that the tube and nozzle, and all parts coming in contact with the paste, must be made entirely of block tin.

It is therefore an object of the present 20 invention to provide a discharge nozzle and a closure therefor which may be made entirely of block tin and which will be as cheap to manufacture as the screw cap now generally used.

25 It is also an object of the invention to provide a construction in which the nozzle will be effectively closed against leakage, in which the closure element is permanently attached to the nozzle and so cannot be removed therefrom and lost, in which the closure may be quickly and easily operated to open or close the discharge opening, and in which the closure cannot be accidentally opened by pressure on the tube.

30 It is a further object of the invention to provide a device of this character which will be entirely sanitary.

With the foregoing and other objects in view I have devised the construction illustrated in the accompanying drawing, in which

35 Fig. 1 is a side elevation of one end of a collapsible tube, showing my improved discharge nozzle applied thereto, the nozzle and closure being shown in section taken substantially on line 1—1 of Fig. 2, and showing the closure in open position.

40 Fig. 2 is a partial end elevation and a partial section substantially on line 2—2 of Fig. 1.

45 Fig. 2* is a longitudinal section through the closure showing its shape before it is applied to the tube.

55 Fig. 3 is a view similar to Fig. 1 but showing the closure in closed position, the section being taken substantially on line 3—3 of Fig. 4.

Fig. 4 is an end elevation of the nozzle looking from the right of Fig. 3.

50 Fig. 5 is a side elevation of the end of the nozzle with the closure removed.

Fig. 6 is an end elevation thereof.

55 Fig. 7 is a longitudinal section through the closure, shown in Figs. 1 to 4, the section being taken substantially on line 7—7 of Fig. 8.

Fig. 8 is an end elevation of the closure looking from the right of Fig. 7.

60 Fig. 9 is a partial side elevation and a partial longitudinal section of a slightly different construction of nozzle, the section being taken substantially on line 9—9 of Fig. 10.

65 Fig. 10 is an end elevation of the nozzle shown in Fig. 9 and looking from the right of this figure.

Fig. 11 is a longitudinal section through the closure of Figs. 9 and 10, taken substantially on line 11—11 of Fig. 10.

70 Fig. 12 is a side elevation of the end of the nozzle shown in Fig. 9 with the closure removed, and

75 Fig. 13 is an end elevation thereof.

80 Referring to the form of nozzle shown in Figs. 1 to 8 the body of the tube is shown at 15, and leading from the end of this tube is a tubular nozzle 16. This nozzle is preferably formed integral with the body of the tube, but may be formed separately and attached thereto by any suitable means. It 85 has a longitudinal discharge passage 17 communicating with the tube, which passage in the present instance leads through the outer end of this nozzle. Adjacent the outer end of this nozzle is a lateral discharge 90 opening 18 leading from the longitudinal passage 17, and at or adjacent its outer end the nozzle is provided with a flange 19. The closure in this form of device 95 comprises a cap 20, which may be knurled on its outer surface or made polygonal as desired to facilitate rotation thereof, and it comprises two concentric tubular portions 21 and 22 which are spaced from each other when applied to the nozzle, the distance between them being sufficient to allow inser-

100

105

- tion of the flange 19, the inner tube 21 being of a size to closely fit the discharge passage 17 but rotatable therein. When formed and before being applied to the 5 nozzle the outer tube 22 is cylindrical as shown in Fig. 2, but after it is applied to the tube the portion adjacent its free end is rolled or pressed inwardly against the outer surface of the nozzle and behind the 10 flange 19, as shown in Figs. 1 and 3, to coat with the flange to retain the closure on the nozzle. The inner tube 21 is provided with a longitudinal passage 23 open at its inner end to the passage 17 but which 15 is closed at its outer end. This tube 21 also has a lateral opening 24 leading from the passage 23 and so located that it may be brought into alignment with opening 18 by rotation of the closure or cap 20 on the 20 nozzle. The outer tube 22 is slabbed off at one side in alignment with the opening 24 as shown at 25 in Fig. 2. This provides an opening through this outer tube which will be in alignment with the opening 18 25 when the opening 24 is in alignment therewith to allow discharge of the contents of the tube, and will also provide relatively sharp edges 26 on opposite sides of the discharge opening 18 to shear off any paste 30 which may be projecting from this discharge opening when this closure is moved to closing position. It will thus prevent paste remaining on the discharge nozzle to collect dirt and become unsanitary.
- 35 In order that the operator may easily and quickly open or close the nozzle a portion of the flange 19 is removed or it is notched to provide opposed shoulders 27 and 28, and the cap or closure is provided with a projection or lug 29 so located as to be between these shoulders and to coat therewith to limit the rotative movement of the cap or closure in opposite directions. That is, the shoulder 27 and the lug 29 are so located that when the cap or closure is rotated counter-clockwise as viewed in Figs. 40 2 and 4, engagement of this lug with the shoulder 27 will stop this rotation with the opening 24 in alignment with opening 18. 45 When the closure is in this position pressure on the tube 15 will force the contents thereof through these openings. After a sufficient quantity desired has been forced through these openings locations of the cap or closure in the opposite direction or 50 clockwise as viewed in Figs. 2 and 4 will rotate the tubes 21 and 22 to move the discharge opening 24 out of alignment with opening 18 and effectively seal the nozzle, 55 this movement being limited by engagement of the lug 29 with the shoulder 28. During this movement the upper sharp edge 26 will shear off any paste which happens to be protruding from the opening 18. It 60 will be seen that in this position the nozzle 65 is effectively sealed both against drying out of the contents of the tube, and also against leakage and accidental discharge of the 70 contents should pressure be applied to the tube. As the passage 17 and inner tube 21 are cylindrical, a close fit may be easily made so that there is no danger of paste being forced in between the cap or closure and the nozzle. The rolling in of the outer tube 22 gives sufficient frictional engagement between the closure and the outer surface of the nozzle to prevent accidental rotation of the closure on the nozzle.
- 75 Referring to Figs. 9 to 13 I have shown in these figures a slightly different construction of nozzle and closure. In this case the nozzle is indicated at 30 and has a longitudinal discharge passage 31, and this passage is closed at its outer end except for an eccentrically arranged discharge opening 32. The nozzle has at or adjacent its outer end a flange 33 corresponding to flange 19 in the first form, and it is used to secure the cap or closure 34 on the nozzle. This cap or closure does not have an inner tube corresponding to the tube 21 of the first form, but is provided with the outer tube 35 adapted to be rolled in over the flange 33, as in the first form, to permanently secure the closure to the nozzle. 80 This cap or closure is provided with an eccentrically arranged opening 36 adapted upon rotation of the closure on the nozzle to be moved to and from alignment with the opening 32 to allow discharge of the 85 contents of the nozzle or to seal the same. The flange 33 is cut away as in the first form to provide spaced shoulders 37 and 38, and the cap or closure is provided with a lug 39 arranged between these shoulders 90 so positioned that when the closure is rotated counter-clockwise as viewed in Fig. 10 to bring this lug into engagement with the shoulder 38 the openings 32 and 36 will be brought into alignment, and when rotated in the opposite direction to bring the lug into engagement with the shoulder 37 the openings will be moved out of alignment and the nozzle effectively sealed.
- 95 It will be apparent from the foregoing description that the nozzle and closure described may be made of block tin as required by the pure food laws, also that they may be manufactured at as low a cost as the tube closures now generally employed, but as this 100 closure is permanently secured to the nozzle it can not be removed and so can not be lost. Furthermore, the opening and closing operations are much simpler and may be performed in a much shorter time with this 105 closure than with the screw type of closure, a partial rotation of the closure in either direction being sufficient to open and close the nozzle. The nozzle is also effectively closed against leakage or accidental opening 110

- 120
- 125
- 130

should pressure be applied to the tube when the cap is in closing position, and it may be easily kept clean and sanitary at all times.

Having thus set forth the nature of my invention, what I claim is:

1. A collapsible tube having a discharge nozzle provided with a longitudinal passage and a discharge opening leading from said passage, said nozzle being provided 10 with an exterior flange adjacent its outer end, and a movable cap embracing the outer end of the nozzle and provided with means engaging said flange to prevent removal of the cap from the nozzle, said cap being provided 15 with an opening adapted by movement of the cap to be brought into and shifted from alignment with the discharge opening, a portion of said flange being omitted to provide spaced opposed shoulders, and a lug carried by the cap adapted 20 to coact with said shoulders to limit the movements of the cap and properly position the opening therein.
2. A collapsible tube having a discharge 25 nozzle provided with a longitudinal passage and a lateral discharge opening leading from said passage, said nozzle being provided with an exterior flange adjacent its outer end, a cap embracing the outer end of 30 said nozzle engaging said flange to secure the cap to the nozzle, said cap being provided with a tubular portion extending past said discharge opening, said cap being rotatable on the nozzle and its tubular portion 35 being slabbed off at one side to provide relatively sharp edges on opposite sides of the
- discharge opening, a portion of said flange being omitted to provide spaced opposed shoulders, and a lug carried by the cap extending between said shoulders and adapted 40 to coact therewith to limit the movements of the cap and properly position said edges.
3. A collapsible tube having a discharge 45 nozzle provided with a longitudinal passage leading through the outer end thereof and a lateral discharge opening leading from said passage, an external flange on said nozzle adjacent its outer end, a closure cap adapted to embrace the end of the nozzle and provided with concentric tubular portions the 50 inner one of which extends into the outer open end of said nozzle and past said discharge opening, and the outer one of which embraces said flange to secure the cap to the nozzle, the inner tubular portion of the cap 55 being provided with a lateral opening adapted to be brought into alignment with the discharge opening, and the outer tubular portion being slabbed off opposite the opening in the inner portion to provide a passage 60 and comparatively sharp edges on opposite sides of the discharge opening, said cap being rotatable on the nozzle, a portion of said flange being omitted to provide spaced opposed shoulders, and a lug carried by the 65 cap extending between said shoulders and adapted to engage said shoulders to limit the movements of the cap to properly position the opening in the inner tubular portion and said edges.

In testimony whereof I affix my signature.

ROBERT H. LIEBERTHAL.
